(57) **CLAIM**

The ornamental design for a holder for electronic device, as shown and described.

DESCRIPTION

FIG. 1 is a front perspective view a holder for electronic device in a closed position showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front perspective view thereof, shown in an environment of use;

FIG. 9 is a front perspective view of the holder for electronic device of FIG. 1, shown in an open position;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is a front perspective view thereof, shown in an environment of use.

Broken lines and regions bounded by broken lines illustrate portions of the holder for electronic device that form no part of the claimed design. Additional broken lines in FIG. 8 and FIG. 16 depict environmental subject matter and form no part of the claimed design.

1 Claim, 16 Drawing Sheets
